UNITED STATES PATENT OFFICE.

GEORGE BREIDENBACH, OF CHICAGO, ILLINOIS.

REMOVABLE CLOSURE.

Application filed April 14, 1922, Serial No. 552,545. Renewed November 30, 1927.

This invention relates to supporting devices, and pertains more particularly to improved means for supporting and retaining a door in an opening, the device of this invention being embodied in a construction adapted to retain a door in a freight car, where the latter is loaded with grain such as wheat, or other material in bulk, and while this invention, for the sake of convenience, is illustrated as embodied in a supporting and retaining means for a grain door for so-called box-cars, it will be obvious that the device finds a wide field of utility for other purposes.

As is common knowledge to those skilled in the art to which this invention is here adapted, it is customary to transport wheat, rye, barley and similar materials in bulk in a so-called box freight car, because such cars afford a complete covering for the contents and thus prevent subjection of the materials mentioned to the elements. However, as this type of car is not ordinarily adapted for employment in carrying a bulk shipment, due to the side door construction, it is necessary that an inner door be placed over each of the side openings for sealing same and for retaining the contents. Such doors are usually made larger in width than that of the side opening and of a sufficient height to retain the contents, the temporary door then being nailed or otherwise secured against displacement during loading and shipment. After the loaded car has been delivered to its destination these doors must be removed before the contents of the car can be released, and as the pressure of the contents on the temporary doors is very great due to settling in transit, it is difficult to remove the doors without partially or completely destroying same or adjacent parts of the car body or door frame, and at best, the removal of the temporary doors consumes considerable time.

It is with the foregoing insufficiencies and objectionable features heretofore employed in view that the present invention has been designed, the invention having for its objects the provision of improved means for supporting and retaining a door; the provision of improved means for supporting and retaining an inner door subject to pressure in the side opening of a box freight car; the provision of improved means for removably supporting a door subject to pressure in the

side opening of a freight car; the provision of an improved means for retaining a grain door without interference with the conventional side door of the car; the provision of improved means for retaining a door and adapted for application to any standard box freight car; the provision of an improved form of closure; and more particularly one characterized by removability without injury and replaceability; the provision of an improved means for retaining a door while subject to pressure and which may be readily removed while the door is under pressure to permit of opening; and the provision of an article of manufacture, possessing the advantageous features outlined above, which is simple, universal in application, efficient in operation and capable of manufacture and installation at low cost. The device is arranged so that it may be placed out of the way when the car is used for merchandise.

This invention is characterized by other features and advantages which will appear or be pointed out as this description proceeds; one embodiment of the invention being illustrated in the accompanying drawings, in which:

Figure 1 is a fragmentary side elevational view of a standard freight car, this invention being applied;

Figure 2 is a vertical transverse sectional view taken on the line 2-2 of Figure 1, looking in the direction indicated by the arrows;

Figure 3 is a horizontal sectional view taken on line 3-3 of Figure 1, looking in the direction indicated by the arrows;

Figure 4 is a fragmentary enlarged detail view;

Figure 5 is a sectional view of a detail;

Figure 6 is a similar view of a modified form of the same detail;

Figure 7 is a fragmentary vertical sectional view of a car structure including a modified form of this invention;

Figure 8 is a transverse sectional view on line 8-8 of Figure 7, looking in the direction indicated by the arrows;

Figure 9 is a fragmentary sectional view of a car structure including another modified form of this invention; and

Figures 10 and 11 are transverse sectional views of alternative forms of the invention as shown in Figure 9.

Referring more particularly to the draw-

ing and first to Figures 1 to 3, inclusive, there are illustrated parts of a standard railway freight car of the conventional box type wherein the car is shown as composed of under frame members 5—5, sides 6—6, floor 7, and roof 8. The sides are composed of the sheathing or siding 9 and lining 10, each side of the car having an opening 11 therein, this opening being substantially 10 rectangular in shape and usually placed about midway the length of the car. As both sides of the car are substantially identical, I will describe but one side and also but one application of the invention, it being understood that the invention may be applied to both doors.

A sliding door 12 is hung on a track 13 and is movable over the outer surface of the side of the car on said track to open and 20 close the opening 11, said door 12 being suspended on said track by rollers 14 and the lower end of the door being held against the side of the car during movement by a series of guide brackets 15—15. This is 25 purely a conventional arrangement and is followed in practically all box car construction.

Referring now to the application of the invention to the box car illustrated, following the usual practice where the car is employed for transporting wheat, rye, oats and other commodities in bulk, there is provided a so-called grain door 16, composed of the planks 17—17, vertical cleats 18—18 and 30 diagonal brace 19, the cleats and brace serving to connect the planks, said cleats being arranged a short distance from the ends of the planks 17. This door 16 is placed inside the car, one edge 20 of the door overlapping the door post 21, an angle-iron 22 or cleat being provided upon and secured to said post for abutting the edge of the door, and the 35 opposite edge 22' of said door lying adjacent the other post 23 and in abutting relation with a displaceable angle-iron 24, secured to one face of the post 23 as will be explained presently. It will be seen from Figure 3 that the grain door, in its proper position is disposed well within the door opening so that there is no interference with the operation of the sliding door 12. The angle-iron 22 serves to prevent endwise or longitudinal movement of the grain door in one 40 direction while the car is in transit or being loaded, the door post 23 and angle-iron 24 preventing endwise movement in the opposite direction.

The displaceable angle-iron 24 is suspended for pivotal and slidable movement from 45 a lag screw or bolt 25, which latter is driven into the adjacent face of the door post 23 near the top of the side opening 11, the angle-iron 24 having an elongated opening 26 through which said bolt passes. The 50 angle-iron 24 terminates a sufficient distance

from the top of the door opening so as to permit vertical sliding movement of said angle-iron on the bolt. The head 27 of the bolt 25 is disposed a sufficient distance from the outer surface of the adjacent flange of the angle-iron, as seen in Figure 1, to permit the latter to loosely move laterally and angularly back and forth on said bolt for a purpose which will presently appear.

For retaining the angle-iron 24 or lock-bar 55 against movement, as shown in Figures 1 to 3, inclusive, there is provided a second lag screw or bolt 28, driven into one face of the door post 23 near the floor of the car, and the adjacent flange of the lock-bar 24 is provided with a slot 29, preferably right-angular in shape and opening at the inner edge of the lock-bar, the slot 29 being slightly flared at its open end for facilitating engagement with the bolt 28. The slot 26 permits the engagement of the bolt 28 with the slot provided therefor, this being accomplished by raising the lock-bar until the bolt 28 enters the slot 29, and then permitting the lock-bar to drop. The lower end 60 of the lock-bar 24 when in the lowered position abuts the door plate 30 and a recess 30' is provided in one flange of the angle-bar to permit of the insertion of a crow-bar 31 (Figure 4) for raising the lock-bar when 65 it is desired to release the door while subject to pressure of the contents of the car. The purpose of the angle-iron 24 engaging the door plate 30 is to prevent the escape of the material held between the edge of the door 16 and the post 23. Additional lag screws and slots therefor may be provided in the lock-bar where the height of the door opening is such that the angle-iron might be subject to flexing. However, this might 70 be readily be taken care of by employing a heavier angle-iron.

As will be seen in Figure 2, the lock-bar 24 is adapted to be swung up into the car when not in use, and will thus be out 75 of the way, it being evident from Figure 2 that the distance between the upper end of the bar and the top plate 31' of the door opening is sufficient to permit such swinging, and the slot 26 is of such length that 80 the upper end of the lock-bar cannot slide outwardly into the path of the sliding door 12.

For supporting the free end of the lock-bar when not in use, there is provided a 85 bracket 32, secured at a convenient point near the roof 8 of the car, two forms of this bracket being illustrated, as in Figures 5 and 6. In Figure 5, the bracket takes the form of a substantially right-angular stirrup, one leg 33 of which is secured by screws 34 or the like to a roof beam 35, the abutment 36 preventing accidental dislodgement 90 of the lock-bar. In Figure 6, the bracket is provided with a base portion 37, secured 95

to the roof 8 itself, this form of the bracket being employed where no beam is conveniently present. The slight lateral movement of the lock-bar permitted by spacing the head 27 of the bolt 25, as shown, readily accommodates the bar to the required movement when seating same in the stirrup.

From the foregoing it will be seen that the inner or temporary door 16 is rigidly retained in position against the pressure of the contents of the car, and that the removal of the door, even though under great pressure, may be quickly and facilely accomplished by the use of the crow-bar as previously mentioned. This means a great saving in time while the cars are at the pits where the unloading takes place, and thereby reduces the time required for unloading and consequently releases the car from the siding sooner.

With reference to Figures 7 and 8, there is provided a modification wherein the door post is shown at 38, this post being of the standard wooden construction. In this arrangement the door post is provided on the face 38' with a fulcrum plate 39, near the top of the side opening, said plate being secured to the post by screws 40, or the like, and said plate having a vertical substantially central slot 41. In this instance the lock-bar 24' takes the same form as the bar 24 but said bar 24' is provided with a fixed bearing stud 42, said stud lying within the slot 41. A lock plate 43 is secured by screws 44 to the face 38' of the post 38, relatively close to the floor of the car, said plate having a slot 45 therein provided with a notch 46 into which the lock-stud 47 drops, said stud also being fixed on the angle-bar 24'. The studs 42 and 47 are substantially identical, the latter only being fully shown, and comprising a shank reduced at 48 to enter the angle-bar 24', and riveted at 49. The outer end of the studs each have a nut 50 thereon, there being provided sufficient play between the nuts and the plates 39 and 43 to permit the lock-bar to be swung into the car when not in use. The post 38 is provided with an elongated recess 51 for accommodating the stud 47, and a recess, not shown, is also provided for the stud 42. This form of the invention eliminates all projections from the door post into the opening, such as might interfere with loading merchandise. However, both forms so far described produce efficient and desirable results.

Referring now to Figures 9 and 10, an application of this invention to a steel door post 52 is there shown. There are a number of different styles of steel door posts, but that shown will serve to convey the idea here. In this instance, the lock-bar 53 is pivotally and slidably mounted upon the stud 54, carried fixedly on the face 54' of the

door post, a slot 55 in one flange of the lock bar serving to engage the stud. The door post is slotted at 56, similarly to the slotted plate 43 hereinbefore described, and a lock stud 57 is provided on the lock-bar 53 near the lower end thereof and is adapted to enter said slot 56. The stud 54 is best shown in Figure 10, said stud having a reduced shank 58 riveted at 59 in the door post, the enlarged portion of the stud entering the slot 55 and being provided with a head 60.

In some instances the door post of metal is hollow, that is, there is no wooden post within the steel casing, and in this event the stud 57 may be modified as shown in Figure 11. Here the stud, designated 57' is loosely mounted in the steel casing 61, and said casing is provided with a countersunk opening for receiving the head of the stud when not in use, the stud being withdrawn until the nut 62 thereon abuts the casing, whereupon the lock-bar, in this instance similar in construction to that shown in Figure 1, may be engaged therewith. It will be readily seen that the several forms of this invention shown readily adapt the device to use on the various types of box freight doors.

Having thus described my invention and illustrated its use, what I claim as new and desire to secure by Letters Patent is:—

1. In combination, a container for material in bulk, said container having a side opening and a side post, a closure within said container for said opening, a bar on one side of said opening, and means fixedly mounted on the post and with which said bar is slidably engageable for holding said bar for retaining said closure only against pressure from within the container.

2. In a device of the character described, in combination, a vertical post forming one side of an opening, a floor, a closure for said opening, a flanged element pivotally and slidably mounted on a fulcrum on said post immediately adjacent to the top of the opening, means on the post for locking said flanged element in vertical alinement therewith by movement of the flanged element in two planes, and the lower end of said flanged element being recessed to afford a space wherein a tool may be inserted in contact with said flanged element and the floor for disengaging said element from said locking means.

3. In a device of the character described, in combination, a container having an opening in a vertical partition thereof, a door arranged in said opening overlapping one edge of the opening and held against the partition solely by the pressure of the contents of said container, a pivoted bar on one side of said opening against which said door abuts, and a bracket in said container above the pivot of said bar onto which one end

of said bar may be engaged out of the way of the contents of said container when the bar is not in use.

4. In a device of the character described, in combination, a vertical post forming one side of an opening, a closure for said opening, a flanged element for retaining said closure in the opening, said flanged element being pivotally and slidably mounted upon said post, a locking stud on the post, and said flanged element having sliding engagement with said locking stud in two angularly related planes.
5. In a device of the character described, in combination, a vertical post forming one side of an opening, a closure for said opening, a flanged element for retaining said closure in the opening, said flanged element being pivotally and slidably mounted upon said post, a locking stud on the post, said flanged element having a right angularly

shaped slot for reception of and engagement of the flanged element with said locking stud for retaining said flanged element in alinement with the post.

6. In a device of the character described, in combination, a vertical post forming one side of an opening, a closure for said opening, a flanged element for retaining said closure in the opening, said flanged element being pivotally and slidably mounted upon said post, said flanged element having a slot therein permitting lateral and vertical movement thereof in engagement with said locking stud, said flanged element in one position engaging the bottom of the opening and having a recess to permit insertion of an implement to raise the flanged element for disengaging same from said locking stud.

In testimony whereof I have hereunto signed my name.

GEORGE BREIDENBACH.
